PACKAGE SEALING MEANS

Andrew W. Anderson, Nutley, N.J., assignor to Scandia Packaging Machinery Company, a corporation of New Jersey

Application March 7, 1957, Serial No. 644,668

5 Claims. (Cl. 53—379)

This invention relates to package sealing means and particularly to means for supporting and holding a package in position for sealing a wrapper therearound.

More particularly stated, the invention relates to supporting and stiffening or holding means for reinforcing and holding a non-rigid or non-supported wall of a package while a wrapper is being sealed around the package and against said wall.

The invention has for its salient object to provide simple and practical means for reinforcing, stiffening and supporting a non-rigid or flexible wall of a package in position as it is fed along a heating or sealing plate or bar.

Further objects of the invention will appear from the following specification taken in connection with the drawings which form a part of this application, and in which:

Fig. 1 is a top plan view of mechanism embodying the invention;

Fig. 2 is a vertical sectional elevation through the mechanism shown in Fig. 1, taken on section line 2—2 of Fig. 1, looking in the direction of the arrows;

Fig. 3 is a side elevation of a portion of the mechanism shown in Fig. 1, this view being broken away;

Fig. 4 is an enlarged sectional elevation through an end portion of the package showing the operation of the stiffening, positioning, and holding means for holding a wall of the package against the sealing bar or plate;

Fig. 5 is a perspective view of a package; and

Fig. 6 is a plan view of the package, partly broken away to show the sections thereof.

In the embodiment of the invention illustrated, the mechanism embodying the invention has been shown in connection with a package P, in which a wrapper is wrapped around a plurality of open-ended compartments C. Each of the compartments C has four walls 10, 11, 12 and 13 which form a rectangular enclosure and in this enclosure there is supported a pouch or pocket 14, preferably formed of thin, transparent plastic material, such as cellophane or like material. This pouch 14 is supported as particularly shown in Fig. 4 on the upper surfaces or upper edges of the four walls of the compartment. The wrapper W is wrapped around the upper and lower surfaces and ends and sides of the package P and the ends of the wrapper are folded and wrapped across the ends 15 and 16 of the package. These ends of the wrapper overlap and are fed through the machine in contact with a pair of heater bars 20 and 21. As they are fed along the heater bars the wrapped ends are sealed. The wrapper may be formed of any suitable wrapping material, such, for instance, as a self-sealing cellophane material. In this case, when the folded ends pass through the machine in contact with the heater bars they would be sealed by the action of the heat thereon.

From the foregoing description it will be evident that since the compartments C are open at both ends there is relatively no stiffness to the package and the present invention has been designed for the purpose of providing means for holding the outer walls of the two end com-

partments flat against the heater bars 20 and 21 as the package is fed through the machine, attention being directed particularly to Fig. 4.

It is assumed that the package P has been formed by 5 wrapping a wrapper around the four compartments arranged side by side and the ends of the wrapper have been folded across the ends 15 and 16 of the package. The packages thus formed are supported on a table 30 which is mounted on uprights 31 and 32 supported on 10 a base 33. The packages are positioned between plates or bars 35 and 36 mounted on conveyor chains 37 and 38 supported in any suitable manner above the table 30. As the conveyor chains 37 and 38 are driven in a manner not shown, the packages will be moved along the table 30 and between two sets of stiffening and wall supporting means about to be described.

Each set of the stiffening and positioning means comprises a plurality of sets of rollers 40 and 41 which are mounted on arms 42 and 43 pivoted on rods 44 and 45 20 supported on a plurality of vertical posts 46 mounted on the base 33. The arms 42 and 43, as shown in Fig. 1, are mounted between collars 48 on the rods 44 and 45 and the arms can swing on the rods.

Adjustable means are provided for limiting the movements of the rollers 40 and 41 toward the upper and lower surfaces of the package and it will be noted in Fig. 25 4 that the rollers engage these surfaces of the package at the outer walls of the outer compartment C and hold these walls flat against the heater plate 20 or 21. The 30 wrapper is tightened by the action of the rollers on the outer walls 10 or 12, as the case may be, and the overlapping ends of the wrapper are stiffened and held tightly against the heater bar. The heat from the heater bar then acts on the adhesive material, which may be in the 35 form of a solvent or other suitable adhesive, and tightly seals the wrapper around the package.

The movement of the rollers against the upper and lower edges of the outer wall is controlled by means of a plurality of disks 50 and 51 mounted on rods 52 and 53, which in turn are mounted on the posts 46. The rods 52 and 53 can be oscillated or rotatably adjusted by arms 54 and 55 and due to the eccentric mounting of the disks 50 and 51 thereon these disks will cause the arms 42 and 43 to swing about the rods 44 and 45. The arms 42 and 43 and the rollers 40 and 41 carried thereby are moved against the edges of the outer wall by means of springs 60 and 61 which, at their outer ends, are hooked around the rods 52 and 53, and at the other ends thereof pass through bores 62 and 63 in the arms 50 42 and 43 and are secured to pins 65.

The adjusted positions of the arms 54 and 55 are controlled by a stud 66 which extends through slots 67 and 68 in the arms 54 and 55 and has mounted thereon a wing nut 69.

55 From the foregoing description it will be clear that the packages P, which consist of open-ended compartments C around which a wrapper has been wrapped with the ends of the wrapper folded across the ends 15 and 16 of the package in overlapping relation, will be fed 60 along the table 30 between the plates or bars 35 and 36 carried by the conveyor chains 37 and 38. As the packages are fed along the table the two sets of rollers will engage the outer surfaces of the wrapper at the upper and lower edges of the outer walls thereof and will exert 65 pressure to flatten the walls and hold them firmly and rigidly against the heater bars, which will cause the adhesive to seal the overlapping ends of the wrappers.

Although one specific embodiment of the invention has been particularly shown and described, it will be understood that the invention is capable of modification and that changes in the construction and in the various 70 cooperating parts may be made without departing from

the spirit or scope of the invention, as expressed in the following claims.

What I claim is:

1. In a wrapping and sealing machine, a heater bar engageable with lapped ends of a wrapper around an article for sealing said ends, means for feeding wrapped articles having walls along the heater bar with the lapped ends of the wrapper contacting the bar, and means engaging and pressing against the inner surface of the wall of the package having the lapped ends of the wrapper for holding the wall and lapped ends firmly against the bar as the package is fed.

2. In a wrapping and sealing machine, a heater bar engageable with lapped ends of a wrapper around an article for sealing said ends, means for feeding wrapped articles having walls along the heater bar with the lapped ends of the wrapper contacting the bar, and means engaging and pressing outwardly the inner surface of the upper and lower edges of the end wall of the package for holding the wall of the package having the lapped ends of the wrapper and lapped ends firmly against the bar as the package is fed.

3. In a wrapping and sealing machine, a heater bar engageable with lapped ends of a wrapper around an article for sealing said ends, means for feeding wrapped articles having walls along the heater bar with the lapped ends of the wrapper contacting the bar, and adjustable means engaging and pressing outwardly the inner surface of the upper and lower edges of the wall of the package having the lapped ends of the wrapper for holding the

wall and lapped ends firmly against the bar as the package is fed.

4. In a wrapping and sealing machine, a heater bar engageable with lapped ends of a wrapper around an article for sealing said ends, means for feeding wrapped articles having walls along the heater bar with the lapped ends of the wrapper contacting the bar, and rollers engaging and pressing outwardly the inner surface of the upper and lower edges of the wall of the package having the lapped ends of the wrapper for holding the wall firmly against the bar as the package is fed.

5. In a wrapping and sealing machine, a heater bar engageable with lapped ends of a wrapper around an article for sealing said ends, means for feeding wrapped articles having walls along the heater bar with the lapped ends of the wrapper contacting the bar, and adjustable rollers engaging and pressing outwardly the inner surface of the upper and lower edges of the wall of the package having the lapped ends of the wrapper for holding the wall firmly against the bar as the package is fed.
